EXTRACTION OF HYDROCARBON OILS

John I. Slaughter, Whiting, Ind., David A. McCaulay, Chicago, Ill., and Arthur P. Lien, Highland, and Carl E. Johnson, Griffith, Ind., assignors to Standard Oil Company, Chicago, Ill., a corporation of Indiana

Application April 27, 1955, Serial No. 504,172

10 Claims. (Cl. 196—13)

This invention relates to the extraction of hydrocarbon oils and in particular it concerns the treatment of hydrocarbon oils with phosphoric acid and BF_3 as the selective solvent.

Hydrocarbon oils such as petroleum and the various fractions thereof, coal tar distillates, shale oils and the like are generally comprised of a mixture of different types of compounds. They may contain aromatic, aliphatic, and alicyclic hydrocarbons as well as sulfur compounds, nitrogen compounds and the like. It is frequently desirable that hydrocarbon fractions be produced free from one or more of several types of these compounds. The petroleum refiner generally desires to remove sulfur compounds from petroleum or the various fractions thereof, such as gasoline, kerosene, burning oils, etc. The presence of aromatic hydrocarbons in kerosene causes the latter to burn with a smoky flame and removal of the aromatic hydrocarbons is often necessary. Condensed ring aromatics lower the viscosity index of lubricating oil stocks and consequently their removal from such a stock is highly desired. The quality of various other petroleum fractions available to the refiner should similarly be refined to remove undesired components such as the aromatic hydrocarbons, sulfur compounds and the like.

Hydrocarbon oils frequently contain components such as polyalkyl benzenes and polynuclear aromatics whose recovery may be desirable. The separation of polyalkyl benzenes and polynuclear aromatics in high purity has become more important in recent years because of the growing demand for particular aromatic hydrocarbons for use in the manufacture of synthetic materials. The manufacture of fibres, plastics, and synthetic intermediates frequently dictates that a specific aromatic hydrocarbon (free of the isomers usually associated therewith) be employed as the initial raw material. The recovery of a single isomer of an aromatic hydrocarbon from its admixture with various other hydrocarbons including its isomers is an exceedingly difficult problem.

An object of this invention is to provide a method of treating hydrocarbon oils to remove undesirable components therefrom. Another object is to provide a method for extracting aromatic hydrocarbons and sulfur compounds from hydrocarbon oils. A further object is to provide a process for the separation of polyalkyl benzenes according to their structural configuration. Numerous other objects and advantages of the present invention will be apparent from the detailed description thereof.

It has been discovered that polyalkyl benzenes, polynuclear aromatics and organic sulfur compounds can be extracted from hydrocarbon oils by the use of a solvent consisting of phosphoric acid having a certain P_2O_5 content and BF_3 employed in excess of a certain minimum amount. The phosphoric acid should have a P_2O_5 content between about 60 and 83% by weight, preferably between about 71 and 80% by weight. The BF_3 is employed in excess of that amount which saturates the

phosphoric acid. This excess amount of BF_3 is at least one mole per mole of extractable component which is desired to be removed from the hydrocarbon oil undergoing treatment. The BF_3 is preferably employed in an amount sufficient to provide a partial pressure of BF_3 in the extraction zone of above about 50 p. s. i. g. usually about 50 to 3000 p. s. i. g. The phosphoric acid is employed in an amount at least sufficient to form separate extract and raffinate phases. The extraction may be carried out at a temperature between about -40° F. and 500° F., preferably at a temperature below about 125° F. After thorough mixing of the phosphoric acid and BF_3 with the hydrocarbon oil, the raffinate and heavier extract phases which are formed are separated. The raffinate and heavier extract phases are separated while in the presence of BF_3 in an amount in excess of that required to saturate the phosphoric acid. Components such as polyalkyl benzenes, polynuclear aromatics or sulfur compounds which have been extracted from the oil and are now contained in the extract phase are separated therefrom.

It has also been found that the extracted components can be separated from the extract phase by removing BF_3 therefrom. This may be done by reducing the pressure in the separated extract phase. If the phosphoric acid employed has a P_2O_5 content of about 71 to 80 weight per cent, reducing the pressure in the separated extract phase to atmospheric pressure will flash off BF_3 and spring extracted components from our solvent. The lighter extracted components can then be removed from the heavier acid layer and the latter recycled to the extraction process together with the recovered BF_3 . When the phosphoric acid employed has less than about 71% or greater than 80% by weight of P_2O_5 , it is usually necessary to resort to other techniques of separating extracted components from the extract phase. For example, the extract phase may be subjected to conditions of elevated temperatures and sub-atmospheric pressures to remove BF_3 and spring extracted components therefrom. Alternatively the extract phase may be diluted with water to spring extracted components. This latter method is not a preferred one.

We have also discovered that it is possible to separate polyalkyl benzenes from each other as well as from aliphatic and alicyclic hydrocarbons which may be contained in the oil. The separation of polyalkyl benzenes is based on their structural configuration. It depends to a great extent upon the number of alkyl substituents in the polyalkyl benzene molecule and the location of the alkyl substituents in the benzene ring.

The phosphoric acid which is employed in our invention has a P_2O_5 content of between about 60 and 83% by weight. Expressed in another fashion, orthophosphoric acid having an H_3PO_4 content of about 85 to 115% by weight is used. This range of phosphoric acids includes orthophosphoric, pyrophosphoric, and polyphosphoric acids. Phosphoric acids containing more than 100% by weight of H_3PO_4 are believed to contain varying amounts of orthophosphoric, pyrophosphoric, and various chain length polyphosphoric acids. It appears that there is an equilibrium mixture of the many phosphoric acids which correspond to a given ratio of H_2O to P_2O_5 . It is preferred to employ a phosphoric acid which has a P_2O_5 content of at least about 71 weight per cent and preferably not higher than about 80 weight per cent. As the P_2O_5 content of the phosphoric acid is increased, its viscosity increases. The phosphoric acids which have a P_2O_5 content higher than about 83 weight per cent are extremely viscous. If the P_2O_5 content of the phosphoric acid is increased from about 83 to 89% by weight, the acid becomes exceedingly more viscous until it becomes a solid at about 89 weight per cent.

P_2O_5 , which corresponds to metaphosphoric acid. Fortunately, the introduction of BF_3 into the phosphoric acid reduces the viscosity of the latter. Because of the very difficult problems in physically handling an extremely viscous selective solvent, it is preferred to employ a phosphoric acid which has a P_2O_5 content not higher than about 83 weight per cent preferably not higher than about 80 weight per cent. It has also been noted that metaphosphoric acid is ineffective as a selective solvent when employed with BF_3 .

It has been found that if the P_2O_5 content of the phosphoric acid is as low as about 60% by weight or as high as about 85% by weight, it is not possible to separate the extracted components from the extract phase as easily as is the case when employing a phosphoric acid having a P_2O_5 content between about 71 and 80% by weight. If the phosphoric acid has between about 71 and 80 weight per cent P_2O_5 , it is possible to remove extracted components from the extract phase by releasing the pressure on the extract phase to atmospheric pressure. BF_3 is flashed off and extracted components are sprung from the extract phase. A layer of the lighter extracted components forms above the heavier layer of phosphoric acid containing BF_3 . If the phosphoric acid which is employed has a P_2O_5 content of 60% by weight or 83% by weight, then releasing the pressure on the extract phase to atmospheric pressure causes some BF_3 to flash off but does not cause the separation of extracted components from the extract phase. With these acids it is necessary to employ other methods (which will be discussed later) for separating extracted components from the extract phase.

Surprisingly, it has been found that related phosphorus acids such as metaphosphorus acid, hypophosphorus acid and phosphonic acids are ineffective as selective solvents when employed with the necessary amount of BF_3 . It has been found to be essential to employ phosphoric acids of the above defined compositions.

The phosphoric acid should be employed in an amount sufficient so that it forms a separate phase. The amount of phosphoric acid which may be employed will depend upon the amount of extractable components one desires to remove from the hydrocarbon oil undergoing treatment. In general no more than one mole of extractable component is removed per each phosphorus atom contained in the phosphoric acid which is employed. Thus one mole of orthophosphoric acid will remove a maximum of one mole of an extractable component. One mole of pyrophosphoric acid will remove a maximum of two moles of extractable component. The amount of phosphoric acid which is employed will thus depend upon the amount of such components which it is desired to remove. The greater the amount of acid which is employed, the larger is the amount of extractable components which are extracted from the oil. Approximately 5 to 1000 volume per cent of phosphoric acid based upon oil may be employed. Usually about 25 to 200 volume per cent phosphoric acid based on oil is satisfactory. At the higher ratios of phosphoric acid to oil the phosphoric acid has an enhanced selectivity for the extractable components.

When BF_3 is passed into a phosphoric acid (having a P_2O_5 content of about 60 to 83 weight per cent) the BF_3 continues to be absorbed by the acid until the acid is saturated therewith. British 451,359 discloses that BF_3 may be passed into ortho- or pyrophosphoric acid at a temperature between 20 and 200° F. or thereabouts, and at about atmospheric pressure to saturate the acid. The amount of BF_3 necessary to saturate our defined phosphoric acids is about 1 gram mole of BF_3 per the sum of the gram atoms of phosphorus plus the gram moles of uncombined water contained in the phosphoric acid. For example, if orthophosphoric acid (100% H_3PO_4) is employed, about 1.0 mole of BF_3 is necessary to saturate each mole of the H_3PO_4 since each mole of

H_3PO_4 contains one atom of phosphorus and no uncombined water. If aqueous H_3PO_4 e. g. 85% concentrated H_3PO_4 is used, then it would be necessary to use about 2 moles of BF_3 to saturate each mole of the 85% concentrated H_3PO_4 . If the phosphoric acid is more highly concentrated than 100% H_3PO_4 (viz. has a P_2O_5 content of 72 to 83 weight per cent) the amount of BF_3 in the BF_3 -saturated phosphoric acid will vary only slightly from about 41 to 43 weight per cent.

In practicing our invention, we employ the BF_3 -saturated phosphoric acid together with additional amounts of BF_3 . The amount of BF_3 employed in excess of that required to saturate the phosphoric acid is at least 1 mole per mole of extractable component which it is desired to remove from the oil. While we do not wish to be bound by any theory, it is our belief that a coordination compound or adduct hereinafter called a complex is formed which consists of the BF_3 -saturated phosphoric acid, the BF_3 in excess of that required to saturate the phosphoric acid, and the extractable component. This complex has been visualized as follows:

The complexes which are formed with the various extractable components have varying degrees of stability. To increase the amount of complex formed, BF_3 is employed in an amount larger than would theoretically be necessary to complex with each mole of extractable component. The larger the amount of BF_3 which is used in our extraction process, the greater is the amount of extractable components which are extracted from the oil. In practicing our invention the hydrocarbon oil is contacted with the BF_3 -saturated phosphoric acid in the presence of excess BF_3 . This excess BF_3 which is employed in the contacting zone is usually an amount sufficient to provide a partial pressure of BF_3 in the contacting zone of at least about 50 p. s. i. g. BF_3 partial pressures of 50 to 3000 p. s. i. g. or higher may be employed. To obtain a high degree of extraction of extractable components, a BF_3 partial pressure about 500 and 2000 p. s. i. g. may be employed.

The contacting of the hydrocarbon oil with the phosphoric acid and BF_3 may be effected at any temperature provided the oil and phosphoric acid are in the liquid phase. The BF_3 -saturated phosphoric acid is liquid at temperatures lower than -40° F. Although it is possible to extract at temperatures below about -40° F. (and even lower temperatures are included within the scope of our invention), it is not usually practical to do so since the oil and phosphoric acid become exceedingly viscous. The contacting may be carried out at temperatures as high as 500° F. although temperatures below about 125° F. are preferred in order to avoid side reactions due to the catalytic effects of our solvent. When referring to the solvent of this invention, it is to be understood to mean the defined phosphoric acids saturated with BF_3 plus excess BF_3 necessary to complex with the extractable components. In general the capacity of the solvent for extractable components decreases as the contacting temperature is increased. We prefer to operate at temperatures of from about 50° to about 100° F.

The hydrocarbon oil is contacted with our solvent for a time sufficient for the solvent to extract extractable components from the oil. This time will vary dependent upon the efficiency of contacting or mixing, which in turn depends on factors such as temperature (poorer mixing is obtained at lower temperatures due to increased viscosity) and other variables. Generally the contacting or mixing time may be from 5 to 60 minutes in each extraction stage. Contact times greater than 1 hour may be employed but usually produce no greater efficiency in extraction. A very long contact time especially at a high temperature may result in side reactions of the hydrocarbons due to the catalytic activity of our solvent.

Because of the high viscosity of some hydrocarbon oils,

it may be desirable to carry out the contacting thereof with our solvent in the presence of an inert diluent. Reducing the viscosity of the oil improves the contacting efficiency in the contacting zone and enables a greater degree of extraction. In addition the raffinate phase of a lower viscosity hydrocarbon oil can be separated more cleanly and rapidly from the extract phase. The diluent should be substantially inert to the phosphoric acid and BF_3 . It should not be affected by the catalytic action of our solvent. Additionally, the diluent should be readily separable by distillation from the hydrocarbon oil although in some instances, it may be desirable to leave the diluent in the refined oil. Suitable diluents are pentane, hexane, petroleum ether, cyclohexanes, benzenes, toluene, and various naphtha fractions low in extractable components. Materials such as heptane or octane may suitably be used when the contacting is carried out at about ambient temperatures.

After the hydrocarbon oil has been mixed with our solvent for a time sufficient for the acid to remove extractable components from the oil, the mixture is settled. The solvent containing extractable components settles from the lighter oil. The heavier extract phase is then separated from the lighter raffinate phase. It is highly important that the phases be separated while in the presence of or under the influence of BF_3 in excess of that necessary to saturate the phosphoric acid. The phases are preferably separated while under a partial pressure of BF_3 of above about 50 p. s. i. g., usually about 50 to 3000 p. s. i. g. Separation of the phases is usually carried out under the same partial pressure of BF_3 and at about the same temperatures as existed during the extraction step. If desired, the extract phase may be washed with non-extractable hydrocarbons which serve the function of stripping out components from the extract phase which are not so strongly absorbed therein. The hydrocarbon diluents discussed in the preceding paragraph may be used for this purpose. This washing or stripping of the extract phase improves the selectivity of our solvent extraction process.

After separation of the extract phase from the raffinate phase, the extract phase is treated to recover extractable components therefrom. If the phosphoric acid employed has a P_2O_5 content of between about 71 and 80% by weight, the extracted components can be sprung from the extract phase by reducing the partial pressure of BF_3 which exists therein. As the partial pressure is reduced by venting BF_3 from the separated extract phase, extracted components separate from the solvent. The less stable complexes formed between the extractable components and our selective solvent are the first to decompose. As the partial pressure of BF_3 in the separated extract phase is lowered, additional amounts of extracted components are sprung from the selective solvent and form a separate and lighter layer. It is readily apparent that the reduction of the partial pressure of BF_3 may be stopped at any point to control the amount of extractable components which are sprung from the extract phase. A number of fractions of oil having different characteristics may be separated from the extract phase by reducing the partial pressure of BF_3 , separating the extracted components which have been sprung, and repeating the cycle. During the sprung step an inert hydrocarbon may be employed to wash the extract phase to insure the substantially complete removal of sprung hydrocarbons from the selective solvent. The BF_3 may be rapidly removed from the extract phase at the temperature employed in the extraction step and generally at a somewhat higher temperature. Thus, while BF_3 may be removed from the extract phase at temperatures as high as 500° F. (cracking and other reactions of the extracted components may occur at this high temperature), it is preferred to effect flashing of the BF_3 from the extract phase at a temperature below about 200° F. The BF_3 which is thus flashed from the separated extract

phase may be recycled for further use in the extraction step. Likewise the phosphoric acid layer may be recycled. It is of course necessary to separate extracted components from the fully saturated selective solvent before reusing for further extraction, otherwise no additional extraction will occur.

If the phosphoric acid employed has a P_2O_5 content greater than about 80% or less than about 71% by weight, the extracted components are not separated from the extract phase merely by reducing the partial pressure of BF_3 to atmospheric. Although BF_3 is thereby flashed off, extracted components are not sprung. By subjecting the separated extract phase (after reducing its pressure to atmospheric) to an elevated temperature e. g. as high as 200 to 300° F. and a reduced pressure e. g. as low as 50 to 200 mm. abs., extracted components are sprung from the extract. Thus vacuum distillation can be used to separate extracted components from the extract phase. If desired the extracted components can be sprung from the separated extract phase by treatment thereof with water, preferably cold water or ice. The upper layer of extracted components can then be separated from the lower aqueous layer. It is readily apparent that the use of the preferred phosphoric acid, viz. 71 to 80 wt. per cent P_2O_5 , has very great advantage in the step of recovering extracted components from the extract phase. The solvent can easily be recovered and reused. The water dilution technique in effect destroys the solvent for further use.

The feed to our process may be a hydrocarbon oil which contains extractable components. Polyalkylbenzenes, polynuclear aromatics and organic sulfur compounds and the like can be removed selectively from the oil by the process of our invention. Any of a wide variety of hydrocarbon oils can be charged to the extraction zone. Various fractions obtained from the distillation of petroleum, for example, naphthas, kerosenes, heater oil, lube oils, etc. or the crude oil itself, may be used as the feed stock. Hydrocarbon oil derived from the treatment of the above materials, for example, naphthas obtained from catalytic cracking or hydro-forming or raffinates or extracts from the solvent refining of naphthas or kerosenes, may be employed as the feed oil. The boiling point of the hydrocarbon oil charged is of no especial consequence so long as it contains extractable components. Suitably it may be between about 200° and 750° F. Shale oil and its various fractions are a suitable feed to the process. The so-called light oil from the coking of a coal may also be employed. The liquid products produced during the hydrogenation of coal may be employed as a charging stock to our process.

The raffinate from our process will usually be the desired product because of its reduced sulfur content and its reduced aromatic content. This is usually the case when the charging stock is a lube oil stock, a kerosene or a high sulfur stock which it is desired to desulfurize. Cycle gas oils are also extracted by our process to produce a raffinate of reduced sulfur and aromatic content which is an excellent stock for recycling to catalytic cracking.

It may be desirable to extract hydrocarbon oils for the purpose of recovering aromatic hydrocarbons from the oil. Thus, the extracted components rather than the raffinate oil may be the desired fraction. It is possible by our invention to extract polyalkyl benzenes from other close boiling hydrocarbons. Thus an extract oil rich in polyalkyl benzenes may be recovered and employed as high anti-knock engine fuel. Our solvent does not seem to complex with benzene or toluene alone. If there are extractable components in the feed e. g. polyalkylbenzenes, then benzene and/or toluene are dissolved in the extract phase in larger amounts. The presence of complexed components improves their solubility.

We have also discovered that polyalkylbenzenes can be separated from each other as well as from aliphatic and alicyclic hydrocarbons. The separation of polyalkylbenzenes depends upon their structural configura-

tion. In general the complexes which are formed between the polyalkylbenzene and our solvent become more stable with an increase in the number of alkyl substituents in the benzene ring. Those benzenes which are substituted in the 1,3-position and in the 1,3,5-position form complexes with the solvent which are more stable than those formed from polyalkylbenzenes having the same number of alkyl substituents but substituted in different positions in the benzene ring. The stability of the complex of a polyalkyl benzene with phosphoric acid and BF_3 is reflected by the pressure at which it dissociates. The higher its dissociation pressure, the less stable is the complex. If the extraction of the polyalkylbenzenes and the separation of the extract phase are both carried out at a pressure above the dissociation pressure of a complex of a specific polyalkylbenzene with phosphoric acid and BF_3 , but at lesser partial pressure of BF_3 than the dissociation pressure of a complex of a different polyalkylbenzene with phosphoric acid and BF_3 , a separation between the two polyalkylbenzenes can be made. By taking advantage of the differing stabilities of the complexes of various polyalkyl benzenes with phosphoric acid and BF_3 , a number of separations between polyalkylbenzenes can be effected. 1,3-dialkyl benzenes can be separated from dialkyl benzenes having their alkyl substituents in other positions in the benzene ring. Similarly 1,3,5-trialkyl benzenes can be separated from trialkyl benzenes having alkyl substituents in other positions in the benzene ring. In addition 1,3,5-trialkyl benzenes can be separated from any of the dialkyl benzenes. Also 1,2,3,5-tetra-alkyl benzene can be separated from any dialkyl or trialkyl benzenes and from isomeric tetra-alkyl benzenes. Penta-alkyl benzene can be separated from any polyalkyl benzene having a lesser number of alkyl substituents in the benzene ring, and hexa-alkyl benzene is separable in an analogous manner from polyalkyl benzenes having a lesser number of alkyl substituents.

In another modification of our extraction process, substantially all of the polyalkyl benzenes (or whatever portion of the polyalkylbenzenes is desired) can be extracted from the hydrocarbon oil. After separating the extract phase the BF_3 pressure thereon may be partially released to spring or form an additional raffinate phase. The raffinate phase will contain polyalkylbenzenes whose complexes with our solvent are less stable at lower BF_3 partial pressures. For example, highly aromatic naphtha fractions such as the product of hydroforming may be extracted with our solvent under BF_3 partial pressures of 2000 p. s. i. g. or higher to produce an extract phase containing substantially all of the polyalkyl benzenes contained in the hydroformate. The partial pressure of BF_3 existent in the separated extract phase is then reduced to about 500 p. s. i. g. whereupon a lighter raffinate layer is formed. The raffinate layer is rich in dialkyl and other more completely substituted polyalkyl benzenes which are not substituted in the 1,3,5-positions. The extract is rich in polyalkyl benzenes substituted in the 1,3,5-positions including tri- and higher polyalkyl benzenes. Thus substantially complete separation of polyalkyl benzenes may be made from a hydrocarbon oil and the polyalkyl benzenes may subsequently be separated into fractions which are enriched in differing polyalkyl benzenes.

Our solvent also has catalytic activity for causing the shifting of alkyl groups on alkyl benzenes. The more highly branched alkyl substituents are more mobile. This mobility, which is reflected by the extent of conversion of the alkylbenzenes, increases with temperature, thoroughness of mixing, contact time, ratio of phosphoric acid to alkylbenzene, and increasing chain length of the alkyl substituents in the alkyl benzene. When the alkyl substituent contains more than about 4 carbon atoms, there is a tendency for the side chain to isomerize and even crack. Isopropyl, sec-butyl, and tert-butyl side chains become highly mobile at about 70° F. Temperatures in the neighborhood of 85° or 100° F. are neces-

sary before ethyl side chains become highly mobile. An even higher temperature viz. around 125° F. is needed in order to render methyl side chains highly mobile.

It has been found that our solvent-catalyst is capable of rapidly disproportionating alkyl benzene. When our solvent-catalyst is employed (preferably under a BF_3 partial pressure of 100 p. s. i. g. or higher) at a temperature of 0° to 200° F., alkyl benzene may be disproportionated to produce the symmetrical 1,3,5-trialkylbenzene in a large proportion. A temperature below 200° F. is preferred in the contacting step to minimize the formation of other isomeric trialkyl benzenes. The phosphoric acid is employed in an amount of from 0.25 to 10, preferably about 3 volumes per volume of alkyl benzene feed. A contact time of from 0.25 to 10 hours, suitably about 2 to 6 hours may be employed. For example, ethylbenzene may be contacted with about 3 volumes of pyrophosphoric acid under a BF_3 partial pressure of 500 p. s. i. g. for about 4 hours at about 200° F. to produce 1,3,5-triethylbenzene in large amounts. The production of diethylbenzene is negligible.

It has also been discovered that polyalkyl benzenes such as trialkyl benzene and tetra-alkyl benzene can be isomerized to produce polyalkyl benzene having a high concentration of those polyalkyl benzenes which have alkyl substituents in the 1,3,5-positions in the benzene ring. Our solvent-catalyst is used at a BF_3 partial pressure of about 100 p. s. i. g. or higher. Reaction temperatures of 0° to 200° F. may be employed. A temperature higher than 200° F. causes the formation of larger amounts of polyalkyl benzenes having alkyl substituents other than in the 1,3,5-positions. In general the tetra-alkyl benzenes require somewhat higher temperatures to effect isomerization than do the trialkyl benzenes. The phosphoric acid is employed in an amount of from 0.25 to 10, preferably about 3 volumes per volume of alkyl benzene feed. Contact times of 0.25 to 10 hours or more, preferably about 2 to 6 hours may be used. For example, trimethyl benzenes may be isomerized to 1,3,5-trimethyl-benzene by contacting the feed with about 3 volumes of pyrophosphoric acid under a BF_3 partial pressure of about 500 p. s. i. g. at a temperature of about 125° F. for about 4 hours.

We have also discovered that if ethylbenzene and meta-xylene plus orthoxylene or paraxylene are contacted with our solvent-catalyst, it is possible to produce a xylene fraction which is enriched in the xylene isomers other than metaxylene and an ethylxylene fraction rich in the 1,3,5-isomer. The reaction effect is carried out preferably at a temperature of about 70° to 125° F. although a temperature as low as 0° F. and as high as about 200° F. may be employed. Our solvent-catalyst is employed while using a BF_3 partial pressure of 100 p. s. i. g. or higher, suitably 2000 p. s. i. g. While the volumetric ratio of phosphoric acid to alkyl benzene feed may vary from 0.25 to 10:1, a preferred ratio is about 3:1. A reaction time of 1 to 10 or more hours, preferably about 4 to 8 hours is employed. The extract phase recovered is rich in ethylxylene and the raffinate phase is rich in xylenes other than meta-xylene. In a process modification, the reaction is carried out in two stages. A short contact time e. g. 1 to 2 hours, is used in the first step, following which a phase separation is made. The raffinate phase is enriched in xylene isomers other than metaxylene. The extract phase is reacted for an additional length of time e. g. 1 to 10 hours, to produce a high yield of 1,3,5-ethylxylene. After the reaction has been completed, the products may then be recovered by removing BF_3 from the reaction product and separating the hydrocarbon layer from the phosphoric acid layer. Alternatively, the products may be recovered after the reaction has been completed by separating an extract phase rich in 1,3,5-ethylxylene from the raffinate phase which contains large amounts of benzene and ethylbenzene.

We have also found that mononuclear aromatics can

be alkylated with olefins containing 2 to 4 carbon atoms to produce polyalkyl benzenes having alkyl substituents in the 1,3,5-positions in the benzene ring. The alkylation may be carried out at a temperature of 0° to 200° F., the higher molecular weight olefin being employed at the lower temperatures. A temperature of about 70° F. is used when propylenes or butylenes are employed and a temperature of about 100° F. is employed when ethylene is used. The BF₃ is employed in our solvent-catalyst in amounts to provide a partial pressure of BF₃ higher than about 100 p. s. i. g. The phosphoric acid to hydrocarbon volumetric ratio may be from 0.25 to 10:1 e. g. 3:1. To prepare the 1,3,5-trialkylbenzene, at least the stoichiometric amount of necessary olefins should be introduced. The olefin should be introduced slowly e. g. over a period of 0.5 to 10 hours or more. For example, meta-xylene may be alkylated with ethylene to produce 1,3,5-ethylxylene. Benzene may be converted in a very large proportion to 1,3,5-triethylbenzene by contacting benzene with about three moles of ethylene and about three volumes of pyrophosphoric acid under a BF₃ partial pressure of 500 p. s. i. g. and a temperature of about 75° F. for four hours.

A number of experiments were performed which demonstrate the effectiveness of our invention. The procedure which was followed in the experiments was as follows: The feed oil was charged to a Hastelloy autoclave of 250 cc. capacity. The phosphoric acid saturated with BF₃ was then added to the autoclave. The BF₃-saturated phosphoric acid was prepared by passing BF₃ at room temperature into the particular phosphoric acid employed and at about atmospheric pressure until no change in weight of the phosphoric acid was observed. The autoclave was then pressured with BF₃ to the partial pressure of BF₃ which was desired. In some experiments the phosphoric acid was saturated with BF₃ after introduction into the autoclave. The contents were then mixed for the desired length of time which was usually between 1/2 and 8 hours depending on the effectiveness of mixing. The contents of the autoclave were then settled for about 1 hour. The heavier extract layer was then withdrawn from the autoclave while maintaining the partial pressure of BF₃ within the autoclave. The raffinate layer was then recovered. The BF₃ pressure on the separated extract phase was then released and BF₃ flashed into a liquid nitrogen trap for recovery. From the extract phase, now at about atmospheric pressure, were recovered the extracted components. In certain instances the extracted components were recovered by decantation of the separate layer which formed above the acid layer. In other experiments, depending upon the P₂O₅ content of the phosphoric acid employed, the extract phase was diluted with water at Dry Ice temperatures to spring the extracted components from the extract phase.

The first series of experiments demonstrate the effectiveness of our invention in reducing the sulfur content and the aromatic content of hydrocarbon oils. The hydrocarbon oil employed in run No. 1 was a heavy catalytic cycle gas oil. A West Texas virgin gas oil was employed in run No. 2. The feed to run No. 3 consisted of 4.04 volume per cent diphenyl sulfide in n-heptane. The gas oils which were employed had the following inspections:

	Cycle Gas Oil	Virgin Gas Oil
ASTM distillation range, °F.:		
Initial	430	262
10%	545	506
50%	591	617
90%	641	735
Final	702	769
Gravity, °API at 60° F.:		
Percent aromatics (micro-dye)	52	42
Wt. percent sulfur	1.51	1.85

In extracting the above feed stocks, approximately 100 cc. of feed was contacted with 20 cc. of phosphoric acid, the P₂O₅ content of the phosphoric acid being about 82 weight per cent. A temperature of about 75° to 80° F. and a BF₃ partial pressure of 500 p. s. i. g. were maintained within the autoclave. The contents were mixed for about 2 hours and then settled for one hour to effect stratification. After separation of the heavier extract phase and release of BF₃ pressure therefrom, the extract was diluted with water at Dry Ice temperatures to spring the extracted components. The extent of desulfurization and dearomatization of the raffinate oils were then determined. The treating loss as measured by the volume of oil lost to the extract phase was measured. The results obtained are shown in Table I which follows:

Table I

Run No.	Feed	Percent Desulfurization	Percent Dearomatization	Percent Treating Loss
1.....	Cycle Gas Oil.....	79.0	79.0	32
2.....	Virgin Gas Oil.....	92.0	70.2	22
3.....	Sulfur Compound in Oil.....	94.0	.....	4

The excellent desulfurization ability of our solvent is readily apparent. It is particularly noticeable from run No. 3 where a desulfurization of 94% was attained. The treating loss in run No. 3 was only 4% which corresponds approximately with the 4.04 volume per cent of organic sulfur compound in the feed. The high selectivity of our solvent for organic sulfur compounds makes it very useful in petroleum refining. The ability to remove aromatic hydrocarbons from the charging stock as evidenced by the results of runs No. 1 and 2 makes our process useful in producing a raffinate oil which is an improved charging stock to catalytic cracking for the production of gasoline.

The value of our process in improving the quality of lubricating oil stocks has also been demonstrated. It has been shown that our process is capable of improving the viscosity index by a very considerable amount. In run No. 4 a 20W base stock having a gravity of 22.5° API, a viscosity at 100° F. of 311.4 SSU, a viscosity index of 50, a sulfur content of 1.61 weight per cent, and an NPA color of 3 was extracted with our selective solvent under conditions identical with those discussed in the preceding desulfurization and dearomatization experiments. About 69% of the oil was recovered as a raffinate oil (31 volume per cent treating loss). This oil had a viscosity at 100° F. of 201.2 SSU, a viscosity index of 78, a sulfur content of 0.43 weight per cent (which corresponds to a desulfurization of 81.6%) and was water-white in color. Thus our invention is applicable to the extraction of lube oil stocks to improve viscosity index, lower the sulfur content, and improve the color.

An additional series of runs were conducted which demonstrate the effect of the P₂O₅ content of the phosphoric acid on the manner in which the extracted components can be recovered from the extract phase. The feed employed was 33 volume per cent mesitylene in n-heptane. Phosphoric acids (50 cc. in each run) of differing P₂O₅ contents were used in each run. Hydrocarbon feed was also employed in the amount of 50 cc. per run. The extraction was conducted at a temperature of about 75° to 80° F. and under a partial pressure of BF₃ of 500 p. s. i. g. The contents of the autoclave were mixed for about 30 minutes and then settled for about 30 minutes. The extract phase was withdrawn from the autoclave while under the stated partial pressure of BF₃. The extracted components were then recovered from the

11

separated extract phase. The results obtained are shown in Table II which follows:

Table II

Run No.	Wt. Percent P ₂ O ₅ of Acid	Percent of Mesitylene extracted	Recovery of Extracted Components
5-----	61.6	95	Water dilution.
6-----	72.4	68	BF ₃ depressuring.
7-----	78.9	95	BF ₃ depressuring.

It is important to note from Table II that when the P₂O₅ content of the phosphoric acid was 61.6 wt. per cent (corresponding to 85% concentrated H₃PO₄), the extracted mesitylene could not be separated from the extract phase by depressuring the extract phase to atmospheric pressure to remove BF₃. No separation of mesitylene was observed even though the extract phase was allowed to stand for 12 hours. However, when the phosphoric acid employed had a P₂O₅ content of 72.4 or 78.9 weight per cent, the extracted mesitylene could be recovered from the separated extract phase merely by reducing the pressure on the extract phase to atmospheric pressure. The BF₃ was flashed off and a supernatant layer of mesitylene was formed above the acid layer. The mesitylene was then recovered by decantation. In additional experiments it has been shown that if an extract such as is obtained from run No. 5 is depressured to atmospheric conditions and then heated to about 130° F., while reducing the absolute pressure to 200 mm., some extracted oil separates from the extract phase and can be recovered by decantation.

The importance of employing BF₃ in excess of the amount necessary to saturate the phosphoric acid has been demonstrated in a number of experiments. These experiments also demonstrate the effectiveness of our selective solvent for separating one polyalkyl benzene from a different polyalkyl benzene. The feed to each run was 50 cc. of an equal volume mixture of mesitylene, m-xylene, and n-heptane. The extraction was conducted at a temperature of about 75° F. and under a partial pressure of BF₃ which differed in each run and was in the range of 8 p. s. i. g. to 550 p. s. i. g. The phosphoric acid employed had a P₂O₅ content of 82% by weight. In each run, including run No. 8 which was the first run, 50 cc. of BF₃-saturated phosphoric acid which had previously been used in extracting mesitylene was employed. The reaction mixture was agitated for about 1 to 2 hours and then settled for an equivalent length of time. The extract phase was separated while subjected to the same partial pressure of BF₃ as was employed during the extraction operation. The pressure on the extract phase was then reduced to atmospheric pressure whereupon extracted components were sprung from the extract layer. Analyses of the sprung extract oil and the raffinate oil were then made. The results obtained are shown in Table III which follows:

Table III

Run No.	BF ₃ , p. s. i. g.	Percent Mesitylene extracted	Distribution Coefficient ¹
8-----	8	13	15.3
9-----	110	92	108
10-----	300	94	119
11-----	550	97.6	480

¹ Distribution coefficient is $\frac{(\text{Conc. } M_E)}{(\text{Conc. } M_R)} \frac{(\text{Conc. } X_E)}{(\text{Conc. } X_R)}$ where M stands for mesitylene, X stands for m-xylene, and subscripts E and R stand for extract and raffinate respectively.

The importance of conducting the extraction under a positive partial pressure of BF₃ is readily apparent from the above data. These data are graphically illustrated in Figure 1.

12

A preferred embodiment of our invention will be described with relation to Figure 2 which is a schematic representation of an adaptation of our process for extracting mesitylene from a fraction of hydroformed naphtha. Valves, pumps, and the like have been omitted from the flow diagram of Figure 2 for purposes of clarity.

Phosphoric acid having a P₂O₅ content of 78 weight per cent is introduced from source 11 by way of valved line 12 into vessel 13 which is capable of withstanding high pressures. Anhydrous BF₃ is passed from source 14 by way of valved line 16 into vessel 13. Because saturation of the phosphoric acid with BF₃ is an exothermic reaction, vessel 13 is provided with cooling means 17 to maintain the temperature at not higher than about 30° F. The BF₃ is introduced into vessel 13 so that a partial pressure of BF₃ of about 100 p. s. i. g. is maintained therein. The solvent (which consists of BF₃-saturated phosphoric acid and BF₃ in partial pressure of 100 p. s. i. g.) is passed by way of valved line 18 into the extractor 19 at a point near its top.

Because our solvent is corrosive to ordinary metals, it is usually necessary to employ some material of construction which is not effected by the solvent. Aluminum and Hastelloy have been found to be outstanding with regard to resistance to corrosion by our selective solvent.

Extractor 19 is a single-stage countercurrent extraction column. The hydrocarbon feed is passed from source 21 by way of valved line 22 into extractor 19 at a point not far above its bottom. The hydrocarbon feed employed is a fraction of hydroformed naphtha which boils between about 270° and 400° F. It contains a substantial amount of trimethyl benzenes including mesitylene, other alkylated aromatic hydrocarbons, and associated aliphatic and alicyclic hydrocarbons. The selective solvent is thoroughly mixed with the hydrocarbon feed at a temperature of about 75° F. for about 15 minutes. Approximately 0.5 liquid volume of our selective solvent is introduced per volume of hydrocarbon feed. The BF₃ partial pressure is maintained at about 100 p. s. i. g. within extractor 19 by introducing BF₃ at vertically spaced points in the reactor through a manifolding system represented by valved lines 23, 23a, and 23b. The extract phase which at the bottom of extractor 19 is countercurrently washed with heptane. Heptane is introduced from source 24 by way of valved line 26 into extractor 19 at a point below the hydrocarbon feed inlet 22 and above the withdrawal line 27 by which the extract phase is removed. About 0.2 volume of heptane is employed per volume of hydrocarbon feed.

The extract phase is removed from extractor 19 while under a BF₃ partial pressure of 100 p. s. i. g. and passed by way of line 27 to heater 28. The extract phase is heated to about 100° F. and then passed by way of line 29 into extract decomposer 31. In decomposer 31 the pressure on the extract phase is reduced to atmospheric pressure which causes BF₃ to flash from the extract phase. The flashed BF₃ is removed from decomposer 31 and recycled by way of line 32 either to extractor 19 or into valved line 16 for forming fresh solvent in vessel 13. The liquid extract phase remaining in decomposer 31 is passed by way of line 33 into settler 34. The heavier acid layer is removed from settler 34 and passed by way of line 36 into valved line 12 whereby it is recycled to vessel 13 for the formation of further amounts of selective solvent.

The lighter hydrocarbon layer is removed from settler 34 and passed by way of line 37 into coalescer 38. Coalescer 38 may be a rock salt coalescer or other means effective for removing residual amounts of acid from the oil. The recovered acid is removed from coalescer 38 by way of line 39. If desired it may be reused for the extraction of additional amounts of hydrocarbon feed. The extracted oil is removed from coalescer 38 and passed by way of line 41 into fractionator 42. Here the residual amounts of BF₃ and other low-boiling components including any xylenes present are distilled over-

head. A bottoms fraction containing high boiling materials such as tetramethylbenzenes, ethyltrimethylbenzenes, and the like, is removed. A side-cut consisting of about 95% purity mesitylene is recovered and passed by way of line 43 to storage, not shown. The raffinate phase is removed from extractor 19 and passed by way of line 44 to means for recovering heptane and raffinate oil. The heptane may be recycled to the extractor. The raffinate oil may be neutralized and washed prior to sending to storage.

Thus having described our invention what is claimed is:

1. A process of treating a hydrocarbon oil to separate an extractable component selected from the class consisting of polyalkyl benzenes, polynuclear aromatics, and organic sulfur compounds which process comprises contacting in a contacting zone at a temperature below about 125° F. said hydrocarbon oil containing at least one of said extractable components with about 5 to 1000 volume percent based on said oil of a phosphoric acid having a P_2O_5 content between about 71 and 80% by weight and BF_3 in an amount sufficient to provide a partial pressure thereof in the contacting zone of between about 50 and 3000 p. s. i. g., forming a raffinate phase and a heavier extract phase, separating said phases while under said partial pressure of BF_3 into a raffinate phase and a heavier extract phase containing extractable components, and removing extracted components from said extract phase.

2. The process of claim 1 wherein said contacting is carried out in the presence of a hydrocarbon diluent that is substantially inert to the action of the phosphoric acid and BF_3 .

3. The process of claim 1 wherein BF_3 is released from the separated extract phase to separate extracted components therefrom.

4. The process of claim 3 wherein said extractable component is an organic sulfur compound.

5. The process of claim 1 wherein said hydrocarbon oil is a lubricating oil stock.

6. The process of claim 1 wherein said extractable component is a polyalkyl benzene.

7. The process of claim 1 wherein said hydrocarbon oil contains a mixture of polyalkyl benzenes and wherein only a portion of said polyalkyl benzenes are extracted in said extract phase, the remainder of said polyalkyl benzenes being contained in said raffinate phase.

8. The process of claim 1 wherein said hydrocarbon oil is a petroleum fraction boiling within the range of about 270° and 400° F. which contains trialkyl benzenes, wherein a polyalkyl benzene substituted in the 1,3,5-positions with alkyl groups is recovered from said extract phase.

9. A process of treating a hydrocarbon oil to separate an extractable component selected from the class consisting of polyalkylbenzenes, polynuclear aromatics and organic sulfur compounds which process comprises contacting said hydrocarbon oil containing at least one of said extractable components with phosphoric acid having a P_2O_5 content between about 60 and 83% by weight and BF_3 , said phosphoric acid being employed in an amount in excess of its solubility in said hydrocarbon oil, carrying out said contacting at a temperature below about 500° F. and under a partial pressure of BF_3 in excess of about 50 p. s. i. g., forming a raffinate phase and a heavier extract phase containing extractable components, separating said phases, and removing extracted components from said extract phase.

10. A process of treating a hydrocarbon oil to separate an extractable component selected from the class consisting of polyalkylbenzenes, polynuclear aromatics, and organic sulfur compounds which process comprises contacting at a temperature below about 500° F. said hydrocarbon oil containing at least one of said extractable components with phosphoric acid having a P_2O_5 content between about 60 and 83% by weight and BF_3 , said phosphoric acid being employed in an amount of about 5 to 1000 volume percent based on said oil, carrying out said contacting under a partial pressure of BF_3 of between about 50 and 3000 p. s. i. g., forming a raffinate phase and a heavier extract phase containing extractable components, separating said phases while subject to said BF_3 partial pressure, and removing extracted components from said extract phase.
